UNITED STATES PATENT OFFICE.

EDWIN M. STRAUSS, OF CHICAGO, ILLINOIS.

BUTTON.

No. 853,607.

Specification of Letters Patent.

Patented May 14, 1907.

Application filed January 20, 1906. Serial No. 296,928.

To all whom it may concern:

Be it known that I, EDWIN M. STRAUSS, a citizen of the United States of America, residing at Chicago, in the county of Cook and State of Illinois, have invented certain new and useful Improvements in Buttons, of which the following is a specification.

My invention relates to improvements in buttons and is fully described and explained in this specification and shown in the accompanying drawings, in which

Figure 1 is a perspective view of my improved button; Fig. 2 is a perspective view showing the same in process of being applied to a collar; Fig. 3 is a side elevation of the button, and Fig. 4 is a section in the line 4—4 of Fig. 3.

Referring to the drawings, A, is a base which is preferably substantially flat as shown in the drawings, the said base being of sufficient diameter to prevent its ready removal from the buttonhole and being sufficiently thin to permit it to be inserted through the buttonhole as will hereafter be set forth.

B, indicates the head of my improved button, the same being supported by a suitable neck, b, adapted to receive one or more of the thicknesses of the articles of apparel with which the button is used.

C, is a spiral connection between the neck and base. In the form of the device herein illustrated the lower portion of the spiral, C, is bent into circular form, as shown at c, which is soldered or otherwise secured to the flat base, the connection in the form illustrated making one turn about the periphery of the base, and in contact therewith. Thereafter the connection makes one spiral turn, c', the upper end of this turn being bent toward the center of the button at c'', to support the neck, b.

In the use of my improved button, the buttonhole is first opened very slightly, as

illustrated in Fig. 2, and the base is thrust 45 edgewise through the buttonhole the base remaining substantially parallel to the material in which the hole is formed. In inserting the base, it will be obvious that that portion thereof opposite to the point from 50 which springs the spiral, c', will be first inserted, so that the entire base, with the exception of the extreme edge, can be slid through the buttonhole and underneath the fabric without substantial distortion of the 55 fabric. Thereupon only a very slight bend of the fabric is necessary to spring the entire base beneath the fabric whereupon a half turn of the button will bring the head into a 60 symmetrical position with respect to the hole and the natural spring of the spiral will hold the button in proper position with respect to the hole. After the base is passed through the first thickness of fabric in this manner the head can be passed through other 65 buttonholes in the ordinary way.

My button is particularly advantageous by reason of the fact that it grips the fabric quite firmly regardless of the size or dimensions of the buttonhole, so that it can be 70 used with a badly worn or torn buttonhole, as well as with a perfect new one.

I claim

The combination with a substantially flat circular base, of a spiral springing from a 75 point on the periphery thereof, and extending upward and terminating above the center of the base, and a head of smaller diameter than the base supported by the upper end of said spiral.

In witness whereof I have signed the above application for Letters Patent at Chicago, in the county of Cook and State of Illinois, this 16th day of January, A. D. 1906.

EDWIN M. STRAUSS.
